UNITED STATES PATENT OFFICE.

RUDOLPH STONE, OF CATAWBA, WISCONSIN.

DESIGN FOR A SINGLETREE-HOOK.

SPECIFICATION forming part of Design No. 34,221, dated March 12, 1901.

Application filed February 8, 1901. Serial No. 46,587. Term of patent 14 years.

To all whom it may concern:

Be it known that I, RUDOLPH STONE, a citizen of the United States, residing at Catawba, in the county of Price and State of Wisconsin, have produced a new and original Design for a Singletree-Hook, of which the following is a specification.

This invention relates to a new and original design for a singletree-hook; and the essential feature of the design resides in the design as illustrated in the accompanying drawings, wherein—

Figure 1 is a perspective view of a singletree-hook embodying the design. Fig. 2 is a side elevation of the same.

The design is characterized by a body 1, having rounded or semicircular edges 2 and upper and lower straight edges 3. At the center of the body an enlargement 4 is located

and vertically disposed and continues into a right-angular hook-shaped member 5, with a convex surface 6, an elliptical opening 7, and an upper vertical slot 8, communicating, with said opening. In the central portions of the body, on opposite sides of the enlargement 4, square openings 9 are formed.

Having thus described the invention, what is claimed as new is—

The design for a singletree-hook, herein shown and described.

In testimony that I claim the foregoing as my own I have hereto affixed my signature in the presence of two witnesses.

RUDOLPH STONE.
